UNITED STATES PATENT OFFICE

ROBERT B. ALFONTE, OF CHICAGO, ILLINOIS, ASSIGNOR TO LOUISVILLE FROG, SWITCH AND SIGNAL CO., OF LOUISVILLE, KENTUCKY

RENEWED SWITCH POINT RAIL AND PROCESS FOR RENEWING SAME

Application filed November 4, 1929. Serial No. 404,749.

This invention relates to a method of reclaiming worn, damaged or impaired switch point rails, and the invention has for its object to reclaim, in a manner as hereinafter set forth, a worn, damaged or impaired switch point rail whereby the point of the rail, after the latter is reclaimed or repaired, will be of greater durability than that of the switch point rail in its original state, or as renewed 10 by any other process.

A further object of the invention resides in the reclaiming of a worn, damaged or impaired switch point rail by combining therewith, at the pointed end thereof, a portion of 15 an old, worn track rail which results in a product that is stronger, tougher and more durable than a new switch point rail or a switch point rail that has been reclaimed by forming a new point thereof with new material, as distinguished from a point made from a reclaimed, old, worn track rail. Further, the reclaiming of worn, damaged or impaired switch point rails under my method produces an unusually satisfactory rail at a material 20 decrease in expense with respect to the cost of a new switch point rail due to the fact that the impaired rail is not discarded and further due to the fact of utilizing a part of an old worn track rail to form the renewed 25 point instead of employing new material.

A further object of the invention resides in the reclaiming of worn, damaged or impaired switch point rails in a manner as hereinafter set forth and which is so carried out that the 30 operation of reclaiming is had at a materially less cost than the manner in which the reclaiming is now performed.

With the foregoing and other objects in view the invention consists of the novel steps 35 of the method and product derived therefrom, as hereinafter more specifically described and illustrated in the accompanying drawings showing certain of the steps of the method and further showing the product produced by the method. It is to be understood, however, that changes, variations and modifications may be had relative to the steps of the method which fall within the scope of the claims hereunto appended.

50 In the drawings wherein like reference

characters denote corresponding parts throughout the several views:—

Figure 1 is a fragmentary view in side elevation of a worn, damaged or impaired switch point rail illustrating the appearance 55 thereof after the worn, damaged or impaired pointed end portion has been cut out for repairing to reclaim the rail.

Figure 2 is a view similar to Figure 1 and further showing the filler part cut from an 60 old, worn track rail preliminary to being welded to the cutout end portion of a switch point rail.

Figure 3 is a side elevation of the structure 65 shown in Figure 2.

Figure 4 is a section on line 4—4, Figure 1.

Figure 5 is a sectional view showing the 70 portion of an old, worn track rail cut to provide the filler part, and with the remaining portion of the track rail from which the filler 75 part has been cut shown in dotted lines.

Figure 6 is a section on line 6—6, Figure 2.

Figure 7 is a vertical sectional view illustrating the reclaimed rail at the switch point 75 end thereof.

Figure 8 is a vertical sectional view of the 80 reclaimed switch point rail showing its position relative to a track rail.

Figure 9 is a top plan view of the structure shown in Figure 3 and further illustrating 85 in dot and dash lines the contour of the filler part after being shaved to form the tapered end portion of a switch point rail.

Figure 10 is a top plan view of a track rail showing associated therewith a reclaimed 90 switch point rail in accordance with this invention, and with the rail having a portion thereof fragmentarily illustrated.

The worn, damaged or impaired switch point rail which is to be reclaimed is indicated 95 at 12, and its web, head, full sized base flange and reduced portion of the other base flange at the pointed end of the rail are indicated by numerals 13, 14, 15 and 16, respectively.

The head or tread portion 14 at the switch 95 point end of rail 12 is removed. The upper part of the web 13 at the switch point end of the rail 12 is also removed. The distance of the removal is as desired, preferably from 30 to 48 inches back from the pointed end por- 100

tion of the rail. The web 13 is removed to a point at or near the longitudinal median thereof. The removal of the portion of the web 13 is had in a manner to provide a beveled edge 17 formed of a longitudinal part which merges into an upwardly and rearwardly curved part 19 terminating at the bottom of head 14. The bevel of the edge 17 extends in the same direction throughout. The removal 10 of the head or tread portion 14 of the switch point rail 12 is made to provide the cutaway end of head 14 with a beveled edge 20 forming a continuation of and corresponding to the edge 17.

15 Positioned upon and registering with the edge 17 of the web 13 is a filler part or insert 22 for the cutout portion of the rail 12. The filler part 22 is T-shaped in cross section and includes a head 23 and a stem 24. The stem 20 24 is disposed centrally with respect to head 23. The filler part 22 is cut from an old, worn track rail. The head 23 and stem 24 of the filler part 22 are parts of the head and web of the old track rail. The bottom edge of stem 24 is beveled as indicated at 25 but the bevel is oppositely disposed with respect to the bevel of edge 17. The longitudinal configuration of the bottom of stem 24 is such as to register with the longitudinal configuration of the cutout end of the switch point rail being renewed. When the lower edge 25 of filler part 22 is mounted upon the upper edge 17 of the switch point rail, the head 23 of the filler part 22 is arranged in crude alignment with head 14 of rail 12. As head 14 of rail 12 has been reduced in width to provide rail 12 with a tapered end portion it necessarily follows that the width of head 23, which is normal, will be of greater width 30 than head 14 as indicated in Figure 2. The thickness of stem 24 corresponds to the thickness of web 13. As the bevel of the bottom edge of the stem 24 extends in an opposite direction with respect to the bevel of the edge 17 of web 13, their superposed position 35 preliminary to welding provides a V-shaped groove 26 which is of a length co-extensive with the length of the stem 24. That end of the head 23 which opposes the bevel end 20 of head 14 is beveled, and forms a continuation 40 of and corresponds to the bevel 25 on the bottom edge of stem 24. The beveled ends of the heads provide a continuation of the groove, as at 28.

45 The edge 17 of the rail 12 provides a bevel face having an upper and a lower edge. The edge 25 of the filler part provides a bevel face having an upper and a lower edge opposing respectively the lower and upper edge 50 of the bevel face provided by edge 17 of the rail 12. The opposed edges of the heads 14 and 23 provide oppositely extending, beveled faces having side edges. One side edge of the bevel face on head 14 abuts one side edge of 55 the bevel face on head 23 and the other side

edges of said faces are spaced from each other. One of the abutting side edges of the bevel faces on the heads forms continuations of the top edge of the bevel face provided by edge 17 of rail 12, and the other abutting side edge forms a continuation of the bottom edge of the bevel face provided by edge 25 of filler part. 70

75 The cutting of the bevel on the rails 12 and filler part or insert 22 is had by means of a torch and then grinding smooth with a grinding wheel. The object is to provide a space of sufficient width between the opposed portions of rail 12 and filler part 22, to receive the required amount of metal from a 80 welding rod to form a solid union. The amount of the metal being such as to completely fill such space.

85 The inserts or fillers for reclaiming switch parts are given a special heat treatment so that they will machine more easily and at the same time give them greater toughness to a certain degree.

90 With respect to the treatment of the filler parts, prior to the welding thereof to the rail, they are placed in a charcoal furnace the temperature of which is then raised to 1500° F. and maintained at that temperature for a period of from forty-five to sixty 95 minutes, after which the temperature within the furnace is reduced to an extent to practically cool the parts. The temperature within the furnace is then again raised to 1500° F., at which point the heat is cut off and the parts allowed to gradually cool such an extent to enable them to be handled with the gloved hand. The furnace during the heat treating process aforesaid is maintained air tight. 100

105 When these inserts are autogenously welded in place they are given a special heat treatment by using a carbonizing flame which increases the carbon content and increases the hardness of the material.

110 The treatments considerably increase the wearing qualities of the inserts or fillers and play a very important part in making the inserts or fillers more resistant to wear than the original metal from which the switch parts were made. 115

120 Experiments have proven that an old used track rail has lost its toughness and instead of planing smoothly on a planer, it will crack and chip off under the planing operation. Experiments have also proven that if such an old worn track rail is subjected to heat treatment it has the effect of reestablishing the life of the metal so that it will plane off smoothly and shape down perfectly in the operation of forming a switch point from such old track rail. Further, such heat treatment also produces a metal that is far tougher and far more durable to withstand the hard usage to which a switch point is put, 125 than is a switch point of new bar metal. 130

As to why the foregoing is true, as borne out by numerous experiments, is not shown. One theory is that the constant pounding on an old and worn track rail has tended to shatter the molecules or grain or fibre as it might be called of the metal. At the same time the constant pounding in use has tended to harden and make this metal more compact than it was when new. The bad characteristics of an old worn track rail are that due to usage, it also becomes more brittle and less durable and less tough than new bar stock would be.

Furthermore the old metal does not plane in a manner to make it adaptable for use for renewing switch points, except when it is subjected to the heat treating process outlined herein and which is necessary for reclaiming worn out switch point rails and utilizing for that purpose old track rails that would otherwise be nothing more than scrap. Furthermore, the utilization of these waste products under my process produces a switch point rail that is far more durable than even an absolutely new switch point rail.

When the filler part, treated in a manner as aforesaid is to be attached to the rail, the lowermost corner of the filler part, which would be the bottom edge of its beveled face, is positioned upon the uppermost corner of the web of the rail, such uppermost corner being the top edge of the beveled face of the rail. When the filler part is arranged in the manner as stated, one side of the beveled face on the head thereof abuts the opposing side of the beveled face, on the head of the rail. The positioning of the filler part, with respect to the rail in the manner as stated provides the V-groove or space to receive the metal from the welding rod. When the filler part and rail are arranged relatively to each other as aforesaid, they are clamped in that position and electrically welded with a welding rod to fill the V-groove formed by the opposed beveled faces. After the welding operation the switch point rail 12 appears in plan as shown in Figure 9, with the exception that the groove 28 will be completely filled with metal from the welding rod.

It now becomes necessary to plane down the filler part 22 until it is shaped as indicated by the dot and dash lines D in Figure 9. After the filler part 22 has been planed the switch point of rail 12 will appear in plan as shown in Figure 10 and in cross section as shown in Figures 7 and 8.

The result of the foregoing method is to produce a switch point rail, which has substantially the same appearance as a new switch point rail, but which is stronger, tougher and more durable than a new switch point rail or a switch point rail that has been reclaimed by forming a new point thereon with new bar material as distinguished from a point made from an old used rail.

The old used track rail from which the filler part 22 is taken, is shown in dotted lines in Figure 5 and indicated at A. The filler for the groove 26 and which is provided by the welding rod is indicated at B, Figures 7 and 8. The completed switch point formed by the filler part 22 is indicated at C, Figures 7, 8 and 10. The filler for the groove 28 and which is provided by the welding bar is indicated at E, Figure 10.

The rail when completed is a composite one formed of a pair of parts and a filling integral with said parts. The pair of parts being so formed and arranged relatively to each other to provide a single V-groove opening at one side and closed to the other side of the rail, the filling being coextensive with and completely filling the groove.

It will be understood of course that my invention does not limit me to the use of this method and process merely for the reclaiming of switch point rails, but that the same process may also be used in connection with renewing frog points or other metal parts of machinery and the like that is subjected to extreme wear and tear, by providing such wearing parts with a renewed wearing surface far more durable than the original new stock.

It must also be borne in mind that if desired, the same result might be accomplished by subjecting new stock to a hammering or pounding process substantially identical with that to which an old track rail has been subjected and thereafter submitting the same to the heat treatment, cooling, and welding process to accomplish a result similar to that accomplished by the use of scrap railway rails, and that this would not be a departure from my invention.

What I claim is:

1. In combination, a switch point rail having its tapered portion cut out for a part of its length to provide a recess having a bottom wall and a curved end wall, the latter merging into the former and a beveled surface bordering said cutout, a switch point part positioned in said cutout and having a beveled surface arranged over said other surface and coacting with the latter to provide a single V-groove, and a welding filler positioned in said groove and being welded to the walls of the latter.

2. A composite switch point rail comprising a unitary structure formed of a pair of parts and a filling integral with said parts, one of said parts being of greater length than the other and having a portion of one end cut out and providing with a beveled face bordering the cutout, the other of said parts forming a switch point positioned in said cutout and having a beveled face arranged over the said other beveled face, said beveled faces extending in opposite directions with respect to each other and coacting to provide a V-groove coextensive with said

switch point part, said groove opening at one side and closed at the other side of the rail, and said filling coextensive with and arranged in said groove.

5 3. In combination, a switch point rail having its tapered portion reduced in height for a part of its length, said reduced portion terminating in an upwardly curved part and formed with a bevelled edge, a part of a used 10 track rail having an edge reversely bevelled with respect to the first mentioned edge and shaped to register with the reduced portion of the switch point rail, said opposed edges coacting to provide a substantially triangular groove, a welding filler for said groove, said edges and filler being welded together, and said part of the used track rail being shaped to a point for the switch point rail.

4. A point-rail comprising, as an element 20 thereof, a point-rail proper containing a recess in the upper portion thereof of its pointed end for receiving a separate point section, the end wall of said recess being curved and merging into the bottom wall of 25 said recess.

5. In combination, a point rail proper having a recess in the upper portion of its pointed end formed with a bottom wall and a curved end wall merging into the bottom 30 wall, and a switch point part conforming in contour to the shape of the recess, seated on the latter and welded to said walls.

6. In combination, a switch point rail having its tapered portion cutout for a part of 35 its length, the edge of the cutout being bevelled, a switch point part positioned in said cutout and having a bevelled edge opposing the bevelled edge of the cutout, the bevel edges extending away from each other to 40 provide a groove opening at the corresponding sides of said rail and part, and a welding filler completely filling said groove and welded to the walls of the latter.

7. In combination, a switch point rail having a recess in the upper portion of its pointed 45 end formed with an end and a bottom wall, the end wall being curved and merging into said bottom wall, a switch point part conforming in contour to the shape of and 50 seated in said recess, said part and walls having coacting means to provide a groove opening at corresponding sides of said rail and part, and a welding filler within said groove and welded to said coacting means.

55 8. A point rail comprising, as an element thereof, an insert constituting a separate point section for a recessed part of the point rail proper, said insert having an end edge portion and a bottom edge portion, said end 60 edge portion being curved and merging into said bottom edge portion.

9. In combination, a point rail proper having a recess in the upper portion of its pointed end formed with a bevelled bottom wall and 65 a bevelled curved end wall merging into the

bottom wall, and a switch point part conforming in contour to the shape of the recess, seated on the latter and welded to said walls, the said part having edge portions beveled, the bevel being continuous and extending upwardly from the inner to the outer sides of the insert.

10. A point rail comprising in combination, a point rail proper, and a separate point section mounted therein, said point rail proper and point section having coacting means to provide a V-groove opening at corresponding sides of the point rail proper and said section, and a welding filler completely filling the groove and welded to the walls of the latter.

11. A point rail comprising in combination, a point rail proper, and a separate point section mounted therein, said point rail proper and point section having coacting means to provide a V-groove opening at corresponding sides of the point rail proper and said section, and a welding filler completely filling the groove and welded to the walls of the latter, said groove formed of a stretch disposed lengthwise with respect to the point rail proper and section and an upwardly extending curved stretch merging at its lower end into the inner end of said other stretch.

12. A point rail comprising a recessed point rail proper, and a separate point section mounted in the recessed portion of the point rail proper, said section and point rail having coacting means to provide a groove opening at corresponding sides of the point rail proper and formed of a stretch disposed longitudinally with respect to the point rail proper and section and a stretch leading upwardly from the inner end of the other stretch, and a 100 filler for and welded to the walls of said grooves.

13. A point rail comprising in combination, a point rail proper having a recess formed with a bottom wall and an upstanding inner end wall, said bottom wall inclining downwardly from the inner to the outer side of said point rail proper and said end wall inclining in a rearward direction from the inner to the outer side of said point rail proper, and a separate point section having a bottom edge portion and an inner end edge portion, said bottom edge portion inclining upwardly from the inner to the outer side of said section and said inner edge portion inclining forwardly from the inner to the outer side of said section, said walls and edge portions coacting to provide a V-groove opening at the inner side of the point rail, and a filler for said groove welded to the walls thereof whereby the point rail proper and point section are secured together.

14. A renewed switch point rail comprising in combination, a used switch point rail having a recess at one end terminal thereof formed solely with a bottom wall and an in-

ner end wall, and a switch point section formed of a heat treated, tapered portion of a used track rail, said section having a bottom edge, an outer end edge and an inner end edge, 5 said section positioned in said recess, the said bottom edge, inner end edge, bottom wall and inner end wall being so formed and co-acting to provide a groove opening at the corresponding sides of said used switch point 10 rail and section, and a filling within and welded to the walls of the groove for connecting the section and used switch point rail together to form the renewed switch point rail.

15. A renewed switch point rail having a 16 wearing point consisting of a heat treated part of a used track rail, said part having a bottom edge and an upwardly extending, curved inner end edge.

20 In testimony whereof, I affix my signature
hereto.
